UNITED STATES PATENT OFFICE.

WILLIAM A. GOOCH, OF LAWRENCEBURG, TENNESSEE.

SPARK-ARRESTER.

No. 895,009.

Specification of Letters Patent.

Patented Aug. 4, 1908.

Application filed July 17, 1907. Serial No. 384,160.

To all whom it may concern:

Be it known that I, WILLIAM A. GOOCH, a citizen of the United States, residing at Lawrenceburg, in the county of Lawrence, State of Tennessee, have invented certain new and useful Improvements in Spark - Arresters; and I do hereby declare the following to be a full, clear, and exact description of the invention, such as will enable others skilled in the art to which it appertains to make and use the same.

The present invention has reference to spark-arresters, and it aims to provide an exceedingly simple, inexpensive, and effective device designed for attachment to the smoke-stack of a locomotive and adapted to check the passage of live sparks and cinders therethrough and divert them into a supplemental pipe, whence they are discharged into the fire-box at the rear of the locomotive.

The invention further resides in the provision in connection with the above-mentioned discharge-pipe, of an exhaust fan, by means of which the sparks and cinders are positively drawn thereinto from the main baffle carried by the arrester, and are blown through said pipe.

With the above and other ends in view the invention consists in the particular details of construction, and in the combination and arrangement of parts all as hereinafter fully described, specifically claimed, and illustrated in the accompanying drawings, in which like parts are designated by corresponding reference numerals in the several views.

Of the said drawings, Figure 1 is a fragmental side elevation of a locomotive equipped with the improved spark-arrester, the casing of the latter being partly broken away to illustrate the main baffle. Fig. 2 is an enlarged detail view of the arrester with the casing thereof and the main baffle broken away, to show the supplemental baffles. Fig. 3 is a longitudinal vertical section through Fig. 2. Fig. 4 is a transverse section on the line 4—4 of Fig. 3.

Referring more particularly to the drawings, the numeral 5 generally designates the locomotive, whose smoke-stack 6 has secured thereto, towards its upper end, the arrester 7, into which latter the stack extends a slight distance, as shown.

The arrester comprises an outer shell or casing 8, of frusto-conical shape, which, at its lower end, is connected with a series of pipes 9 communicating with a main discharge pipe

10 carried by the locomotive and having its bent rear end extending into an opening formed in one side of the latter directly above the fire-box. Intermediate its ends the discharge pipe is provided with a rotary fan 12 which is driven in any preferred manner, the walls of said pipe being distended at such point to form the fan casing. The upper end of the stack is provided with a depending peripheral flange 13, which is set at an angle thereto and thus serves to direct the cinders, etc. into the pipes 9.

Disposed within the casing 8 is a main baffle 14, which is likewise of frusto-conical shape and is held in spaced relation to the inner face of the casing by pins, bolts, or similar means, the height of said baffle being approximately equal to that of the casing. This baffle is formed of a series of parallel, concentric horizontal rings 15 which are connected by vertical rods 16, to which said rings are secured at their upper edges. The rings are disposed in spaced relation to each other, and set at an acute angle and inclined 80 downwardly with respect to said rods, so that the sparks and cinders which are deflected against said rings will pass through the openings between the rings into the cylindrical chamber between the latter and the inner face of the shell 8.

Within the main baffle is disposed a series of supplemental baffles 17, 18, and 19, arranged one above the other, the two end baffles being in the form of inverted conical vessels, while the central baffle is frusto-conical and is disposed oppositely with respect to the first-mentioned baffles; in other words, its lower base lies adjacent the base of the baffle 17, while its upper base lies adjacent 95 the apex of the baffle 19. The several supplemental baffles are each formed of sheet steel, and are provided with a series of concentric, horizontal tongues 20 which are struck up therefrom, each tongue being formed of 100 a series of arcuate sections, so that it may be regarded as being approximately circular in shape. The supplemental baffles are preferably secured directly to the rods 16 which connect the rings 15, and are fitted in place 105 with the latter, in the stack; if preferred, however, they may be disposed within the main baffle after the latter has been inserted within the stack, and may be fastened to the latter, or to the main baffle. It will also be 110 understood that the supplemental baffles may be formed of separate rings somewhat

similar to those which form the main baffle. In either construction, however, the tongues are inclined outwardly and upwardly, so that the sparks and cinders, in their upward passage from the stack, will be deflected against the main baffle, and will pass between the rings thereof, as above stated.

From the foregoing description, it will be apparent that the cinders which have fallen 10 through the main baffle will be drawn by the action of the rotary fan through the pipes 9 and 10, and finally discharged directly into the fire-box 11, to be reheated, thus not only preventing the escape of the cinders, and the 15 consequent danger of fires, but also effecting a practically continuous feed of heated gases and of partially consumed cinders to the fire-box.

In addition to the several deflecting baffles 20 already described, there may be provided, if desired, an additional baffle which is in the nature of a series of rings 22 secured to the inner wall of the casing and extending downwardly towards the corresponding rings 15 25 which form the main baffle, the two sets of rings dovetailing, to a certain extent, as shown in Fig. 1. The several rings 15 and 22 and the flanges formed upon the supplemental baffles are preferably perforated, to 30 facilitate the passage of the smoke and steam through the arrester.

The casing of the arrester, as well as the several baffles, may be frusto-pyramidal or pyramidal, rather than frusto-conical, or 35 conical, if preferred, and other changes in the form, size, and material, and disposition, of the various parts may obviously be made under the scope of the appended claims, as the invention is not intended to be limited 40 to the exact details of construction shown and described.

What is claimed, is,

1. A spark-arrester comprising a casing; a main baffle disposed within the casing in 45 spaced relation thereto, to provide a vertical chamber between the baffle and the inner face of the casing, said baffle consisting of a series of spaced parallel rings connected to each other and arranged one above another; 50 and a series of supplemental baffles disposed

one above another within the main baffle and adapted to deflect the sparks through the openings between said rings.

2. A spark - arrester, comprising an inverted frusto - conical casing; a similarly shaped main baffle disposed within the casing in spaced relation thereto, to provide a vertical chamber between the baffle and the inner face of said casing, said baffle consisting of a series of spaced concentric rings connected to each other and arranged one above another; and a series of perforated supplemental baffles disposed one above the other within the main baffle and adapted to deflect the sparks through the openings between said rings.

3. A spark - arrester, comprising an inverted frusto - conical casing; a similarly shaped main baffle disposed within the casing in spaced relation thereto, to provide a vertical chamber between the baffle and the inner face of said casing, said baffle consisting of a series of spaced concentric downwardly - inclined rings connected to each other and arranged one above another; and a series of supplemental baffles disposed one above the other within the main baffle, each of said supplemental baffles being provided with a series of outwardly inclined circular tongues adapted to deflect the sparks through the openings between said rings.

4. A spark-arrester comprising a casing; a main baffle disposed within the casing in spaced relation thereto, to provide a vertical chamber between the baffle and the inner face of the casing, said baffle consisting of a series of spaced parallel rings connected together and arranged one above another; a baffle disposed within said chamber and consisting of a series of rings located one above another; and a series of supplemental baffles disposed one above another within the main baffle for deflecting the sparks through the openings between the first-mentioned rings.

In testimony whereof, I affix my signature, in presence of two witnesses.

WILLIAM A. GOOCH.
